(57) **CLAIM**

The ornamental design for a column impact protector device, as shown and described.

DESCRIPTION

FIG. 1 is a front perspective view of an outer shell of a column impact protector device showing our new design;

FIG. 2 is a rear perspective view thereof;

FIG. 3 is a top view thereof;

FIG. 4 is a front elevational view thereof;

FIG. 5 is a front elevational view of an inner liner of a column impact protector device showing our new design;

FIG. 6 is a front perspective view thereof;

FIG. 7 is a rear perspective view thereof;

FIG. 8 is a top view thereof;

FIG. 9 is a top view of a completed assembled column impact protector device;

FIG. 10 is a front perspective view thereof;

FIG. 11 is a right side perspective view thereof; and,

FIG. 12 is a rear perspective view thereof.
